MICHAEL REDLINGER, OF PORTLAND, OREGON

MACHINE FOR GRADING AND SORTING ACCORDING TO WEIGHT

Application filed June 23, 1930. Serial No. 463,293.

My invention relates to a machine for grading and sorting fruits and similar products by their relative weights, which is automatic in its action and which is capable of being run at extremely high speeds, thus being adapted for quantity grading. Such machine comprises a conveyor adapted to traverse a path longitudinally of the machine and carries a series of cups or carriers pivotally secured to such conveyor. Upon each carrier is a finger riding upon a grading rail extending generally longitudinal of such machine. Such rail diverges slightly from the path traversed by the conveyor and the finger moves outwardly towards its free extremity. The pivotal connection between such finger and the carrier or cup is controlled by a spring or other yielding means and thus when the weight or mass of the article to be graded acting thru such supporting finger exceeds the spring tension, then such cup is permitted to swing into discharging position. Thus such finger forms a fulcrumed lever held longitudinally extended by a spring and when the product of the lever arm acting under the mass of the article being graded, exceeds the resisting force exerted by the spring or other yielding member, then such finger collapses and permits the carrier to move into discharging position.

A further object of my invention is to provide a grader of this character with a relatively short vertically descending rail at the head end and a fixed lateral finger adapted to ride such rail, which rail supports the weight of the carrier and the article to be graded when the latter is being fed on to such carrier. Said rail gradually descends to become out of engagement as such carrier is moved along by the carrier, thereafter permitting the weight of the carrier and the article to be graded to be supported wholly by the laterally extending collapsible finger, which finger bears upon the grading rail and constitutes the separating mechanism.

A further object of my invention is to provide mechanism of this character adapted to be carried in its entirety by the

carriers, such carriers being interchangeable with each other and the grading mechanism being relatively fixed in place on said carriers.

Another and more specific object of my invention is to provide carriers as above set forth with spring or other resilient elements adapted to exert a progressively lessened force resisting the collapse of the finger with relation to the carrier, functioning so that as such finger collapses progressively the discharge will be more abrupt. In attaining this object the finger is arranged so as to be tipped slightly downwardly, approximately five or ten degrees from the horizontal plane, so that such finger rides upon its point and the position of such finger aids the spring, as above described, in attaining such latter object.

A further object of my invention is to provide guide or let-down rails for a grader of the character in which the carriers pivot about a lateral axis with relation to the machine, which guide or let-down rails are relatively resilient and are pendent and fixed only at their upper ends, so that in case any of such carriers in discharged position ride over a quantity of fruit in the grading stations and are forced upwardly against such let-down or guide rails, then, in that event, the latter will yield and swing upwardly to prevent bruising or otherwise injuring the fruit and such parts being pendent and pivoted at their upper ends thus will be moved back to correct position by the next basket or carrier discharging at the station affected.

The above mentioned objects and structural features of my invention are herein-after described with reference to the accompanying drawings, in which:

Fig. 1 is a fragmentary plan view of a grader embodying my invention;

Fig. 2 is a fragmentary longitudinal section taken therethru on the line 2-2 in Fig. 1;

Fig. 3 is a fragmentary transverse section taken on the line 3-3 in Fig. 1;

Fig. 4 is a perspective detail of one type of carrier with a portion of the fabric floor

100

shown as broken away to disclose the operating mechanism of such carrier;

Fig. 5 is a perspective view of another type of carrier embodying my invention, in which the finger is controlled by a coiled tension spring; and

Fig. 6 is a perspective view of still another type of carrier actuated by gravity weights.

10 My improved grader comprises a frame *a* over the top of which a conveyor *b* moves along a path longitudinally of such frame. It is understood that to attain capacity it is common to provide a number of these 15 grading chains on a single frame, but inasmuch as each grading chain is a separate unit and are mere duplications of each other, but one grading element will be described.

Such conveyor is preferably in the form 20 of an endless chain and mounted over two pairs of end sprockets *c*—*c'*, one element of which is driven. The frame is divided into a number of lateral stations by partitions *d* and each of such stations comprises a box 25 or chute. To all of such stations a common endless belt *d'* conveys the articles to be separated. When my machine is used for grading fruit or articles which are easily injured, it is preferable that the floors of 30 such stations be cushioned or the belt be resilient and lie as close as it is practical to the plane of the conveyor, to shorten the drop when the fruit is diverted from such conveyor to the stations.

35 As is shown in Fig. 3, a series of helical resilient members extend obliquely downwardly from the plane in which the carriers support the articles to a point slightly above the lower end of the carriers when 40 pendent after having discharged said articles. One of said helical let-down members is arranged at each of the stations and serves to lessen the abruptness with which said carriers fall from carrying to discharging 45 positions.

Carried by such conveyors and pivotally mounted thereto are a number of carriers or baskets *e* mounted upon laterally extending pins *f*, which constitute the pivotal connection for such carriers or baskets. Such 50 conveyor chains move along between spaced guides *g*, which fit tightly against the exterior of such conveyors and direct such conveyor along a lineal path. The laterally 55 extending pins *f* carrying the baskets *e* are loosely mounted in such conveyor chains and are held in place, because the chains constituting the conveyors are prevented from spreading apart by guides *g*. To disengage 60 said pins with the basket assemblies carried thereby, it is necessary merely to lift that section of the conveyor above the guides and spread such chains apart. This construction permits new baskets and pins to be quickly 65 and easily inserted in said conveyor.

At the head end of such grader is some type of feeding mechanism *h*, which arranges the articles to be graded separately upon the carriers or baskets. At such head end a relatively short receiving rail *i* is arranged, and extending the entire length of the grader is a grading rail *j*. The carriers or baskets *e* are provided with two spaced laterally extending fingers, a fixed finger *k* which is adapted to engage and ride upon the receiving rail, and a pivotally mounted finger *l* which is adapted to engage and ride along the grading rail *j*. The upper active surfaces of such rails are vertically spaced from each other, as are the fingers and the active surface of the receiving rail descends gradually in the direction of motion of the conveyor. At its initial point the receiving rail is spaced a lesser distance than the spacing of the fingers, so that the entire weight of the carriers or baskets is supported by such receiving rail. Such receiving rail is spaced a greater distance at its discharge end so as to permit the weight of the basket and the articles graded to be transferred to and held by the grading rail.

The function of the receiving rail thus is to take the shock of the fruit or other articles being graded when they are originally discharged from the feeder mechanism on 95 to the grading mechanism. The receiving rail is of sufficient length to permit the articles being graded to assume a condition of equilibrium so that the movement of the articles will not affect the action of the grader.

The grading rail, although it extends substantially in a plane longitudinal of the grader and parallel to the path of the grader, diverges slightly therefrom so that at 105 the forward end of the grader the pivotal finger *l* engages the rail adjacent the fulcrum of such finger and at the discharge end of such grader the carrier is supported by the tip or free end of such finger. The 110 finger is held laterally extended by some such means as a spring or by a gravity weight or other yielding devices and such yielding devices are preferably proportioned so as to sustain the weight of the 115 carrier at all points except when the carrier is supported by the extreme tip end of the pivotal finger. At this point the yieldable means is proportioned to permit the collapse of such finger and the movement of 120 the basket to discharge position, so that no articles, no matter how small, will be carried over the end of the grader.

The degree of angularity between the path of the conveyor and the grading rail 125 is adjusted by means of a set screw *m* preferably arranged one at each end of the machine and threaded.

The carrier or basket shown in Fig. 4 is preferably provided with a twisted wire 130

frame *o* having two forward loops *p*, which are adapted to fit loosely about the transverse pin *f*. The rear edge of such basket comprises a relatively wide band *q* fastened to the ends of such wire frame and tipped backwardly therefrom at a substantial angle. The floor of such carrier or basket is preferably made of fabric *r* such as heavy canvas and treated with some moisture resistant material, for example wax or paraffin.

The fixed finger *k* is riveted or otherwise secured to such band *q* and carries an outstanding stop *k'*. The finger *k* includes a strap element which embraces the wire side member of the frame *o* and is thus pivotally secured thereto. The pivotal finger *l* is mounted about such frame and overlies such stop, which is adapted to position the finger in laterally extended position. A twisted wire torsion element *s* engages such finger and tends to hold the latter against the stop *k'*. Means are provided for adjusting the strength of such torsion member, such means comprising a threaded screw *s'*, which tends to distort such element *s* and to increase its effect. Such element *s* distorts in the main upon its section *s2*, which terminates adjacent the forward end of the frame member. Thus as such finger leaves its position against the stop and collapses upwardly and inwardly, the degree which such member distorts is lessened and thus the resistance to movement on the part of such finger is proportionately decreased. The result is that such finger, which collapses and permits the basket to swing downwardly, when overloaded, breaks quickly and the grading is relatively sharp. To further increase this factor the pivotal finger *l*, when engaging the stop *k'*, preferably tips downwardly or towards the fixed finger *k* approximately five or ten degrees from parallelism and thus when the finger rides upon the grading rail *j*, it is supported only by the tip of the finger.

In the type of basket or carrier shown in Fig. 5, the pivotal finger *t* is actuated by a coiled tension spring *u*, which engages a loop *t'* on such finger and tends to draw such finger downwardly against the stop *k'*. With this type of spring element also the spring *u* exerts its greatest force when the finger is extended laterally, as it is in this position that the loop *t'* extends in a plane normal to the pull of the spring and exercises its greatest effective leverage upon said finger.

In Fig. 6 a third modification of carrier is shown, illustrating the use of gravity weights *w* for actuating such pivotal finger, instead of a tension spring as shown in the previous modification. In all other respects the modification shown in Fig. 6 is the same as that shown in Fig. 5 and the weights exercise a progressively decreasing force in the manner, and for the same reason, as the spring in such previous modification.

I claim:

1. A machine for grading articles of the character described by their relative weight, comprising a basket pivotally mounted for discharge, such basket being provided with a laterally projecting finger yieldingly extended to collapse under a predetermined force, a continuous lineal guide rail upon which said finger rests to support said basket in a horizontal plane, a series of stations spaced lengthwise of such rail, means for moving such basket along such rail following a lineal path relatively divergent from the vertical plane of said rail until the finger collapses under the weight of the article being graded acting thru the increased leverage exerted by said finger relatively to its mounting, thereby permitting such basket to swing into discharging position and to release the article carried thereby at one of such stations.

2. A machine for grading articles of the character described by their relative weight, comprising a basket pivotally mounted for discharge, such basket being provided with a laterally projecting finger pivotally mounted at its base and yieldingly extended to collapse under a predetermined force, a continuous lineal guide rail, upon which said finger rests to support said basket in a horizontal plane, a series of stations spaced lengthwise of such rail, means for moving such basket along such rail following a lineal path relatively divergent from the vertical plane of said rail until such finger collapses under the weight of the article acting thru the relatively increased leverage exerted by said finger upon its pivot, thereby permitting such basket to swing into discharging position and to release the article carried thereby at one of such stations.

3. In a weighing type grading machine of the character described, a conveyor following a path traversing a series of spaced stations, a series of carriers movably secured thereto and adapted to support and carry articles to be graded, a rail arranged generally longitudinal of said path, yieldable means extending laterally from and supporting each of said carriers, riding upon and supported by such rail, said means being pivotally joined to said carrier upon an axis extending generally parallel to said path, such rail diverging relatively to such path at an angle predetermined with respect to such stations and to the yielding point of such means.

4. In a weighing type grading machine of the character described, a conveyor following a path traversing a series of spaced stations, a series of carriers movably secured thereto and adapted to support and carry articles to be graded, a rail arranged generally longitudinal of such path, a yieldable finger extending laterally from and

supporting each of said carriers, riding upon and supported by such rail one of said fingers being pivotally joined to said carrier upon an axis extending generally parallel to said path, such rail diverging relatively to such path at an angle predetermined with respect to such stations and to the yielding point of such fingers.

5. In a weighing type grading machine of the character described, a conveyor following a path traversing a series of spaced stations, a series of carriers movably secured thereto and adapted to support and carry articles to be graded, a rail arranged longitudinal of said path, a yieldable spring controlled element extending laterally from and supporting each of said carriers riding upon and supported by such rail said element being pivotally joined to said carrier upon an axis extending generally parallel to said path, such rail diverging relatively to such path at an angle predetermined with respect to such stations and to the yielding point of such spring controlled element.

25 6. In a weighing type grading machine of the character described, a conveyor following a path traversing a series of spaced stations, a series of carriers movably secured thereto and adapted to support and carry articles to be graded, a rail arranged generally longitudinal of said path, yieldable means extending laterally from and supporting each of said carriers, riding upon and supported by such rail said means being pivotally joined to said carrier, such rail diverging relatively to such path at an angle predetermined with respect to such stations and to the yielding point of such means, and devices for adjusting the angular relation between such path and said rail.

45 7. In a weighing type grading machine of the character described, a traveling conveyor, a carrier pivotally secured thereto and adapted to support and carry articles to be graded along a fixed path in such machine and a grading rail arranged generally longitudinal of such path but diverging slightly therefrom, said carrier comprising a yieldable lateral finger pivotally secured thereto and adapted to engage and to be supported in part by such grading rail.

55 8. In a weighing type grading machine of the character described, a traveling conveyor, a carrier pivotally secured thereto and adapted to support and carry articles to be graded along a fixed path in such machine and a grading rail arranged generally longitudinal of such path but diverging slightly therefrom, said carrier comprising a yieldable lateral finger pivotally secured thereto and adapted to engage and to be supported in part by such grading rail, a stop on said carrier with which said finger engages when laterally extended and

yielding means tending to hold such finger in engagement with such stop.

9. In a weighing type grading machine of the character described, a traveling conveyor, a carrier pivotally secured thereto and adapted to support and carry articles to be graded along a fixed path in such machine and a grading rail arranged generally longitudinal of such path but diverging slightly therefrom, said carrier comprising a yieldable lateral finger pivotally secured thereto and adapted to engage and to be supported in part by such grading rail, a stop on said carrier with which said finger engages when laterally extended and yielding means tending to hold such finger in engagement with such stop, and means for adjusting such latter means.

10. In a weighing type grading machine of the character described, a traveling conveyor, a carrier pivotally secured thereto and adapted to support and carry articles to be graded along a fixed path in such machine and a grading rail arranged generally longitudinal of such path but diverging slightly therefrom, said carrier comprising a yieldable lateral finger pivotally secured thereto and adapted to engage and to be supported in part by such grading rail, a stop on said carrier with which said finger engages when laterally extended and yielding means tending to hold such finger in engagement with such stop, such yielding means being proportioned and arranged to exert a force of progressively lessened degree as such finger is moved away from such stop.

11. In a weighing type grading machine of the character described, a traveling conveyor, a carrier pivotally secured thereto and adapted to support and carry articles to be graded along a fixed path in such machine, a grading rail arranged generally longitudinal of such path but diverging slightly therefrom, and a receiving rail arranged only at the head end of such grading rail and spaced therefrom, said carrier comprising two spaced lateral fingers one fixed relatively upon such carrier and adapted to ride such receiving rail and the other yielding and pivotally secured thereto and adapted to ride such grading rail.

12. In a weighing type grading machine of the character described, a traveling conveyor, a carrier pivotally secured thereto and adapted to support and carry articles to be graded along a fixed path in such machine, a grading rail arranged generally longitudinal of such path but diverging slightly therefrom, and a receiving rail arranged only at the head end of such grading rail and spaced therefrom, said carrier comprising two vertically spaced lateral fingers one fixed relatively upon such carrier and adapted to ride such receiving rail and the

other yielding and pivotally secured thereto and adapted to ride such grading rail.

13. In a weighing type grading machine of the character described, a traveling conveyor, a carrier pivotally secured thereto and adapted to support and carry articles to be graded along a fixed path in such machine, a grading rail arranged generally longitudinal of such path but diverging slightly therefrom, and a receiving rail arranged only at the head end of such grading rail and spaced therefrom, said carrier comprising two vertically spaced lateral fingers one fixed relatively upon such carrier and adapted to ride such receiving rail and the other yielding and pivotally secured thereto and adapted to ride such grading rail and a stop on said carrier when laterally extended, and yielding means tending to hold such finger in engagement with such stop.

In testimony whereof he has affixed his signature.

MICHAEL REDLINGER.
